Attorney.

UNITED STATES PATENT OFFICE.

FRANCIS A. NOLAN, OF ST. PAUL, MINNESOTA.

RUBBER HEEL.

1,219,991.

Specification of Letters Patent. Patented Mar. 20, 1917.

Application filed July 17, 1916. Serial No. 109,654.

To all whom it may concern:

Be it known that I, FRANCIS A. NOLAN, a citizen of the United States, residing at St. Paul, in the county of Ramsey and State 5 of Minnesota, have invented a new and useful Improvement in Rubber Heels, of which the following is a specification.

This invention relates to improvements in cushion heels of that class in which the heel 10 is adapted to be nailed on to the shoe. More particularly the object of the present invention is to provide improved means for causing the nails to most effectively secure the rubber heel on to the shoe. It has been 15 common practice to provide rubber heels with metallic washers or metallic plates embedded therein, and formed with nail holes but as commonly constructed the nails must be made to register with the holes in 20 the embedded washers or plate, in order to insure that the nails pass directly and not slanting therethrough. Where the washers or plates are provided with holes more than the number of nails which are used for 25 securing the rubber heel on the shoe, such washers or plates are necessarily weakened. The object of the present invention is to provide the heel with a plate preferably of metal embedded therein, and so constructed 30 that the nails when driven through the heel and into the shoe will perforate the plate without the necessity of guide holes being previously made in the rubber to register 35 with the points at which the plate is perforated.

To these ends my invention comprises the features of construction and combination of parts hereinafter more particularly described and defined in the claims.

40 In the drawing, Figure 1 is a plan of a rubber shoe heel, a portion thereof being broken away and in section to disclose the plate which is embedded therein; Fig. 2 is a section taken upon the line X—X of Fig. 1; Fig. 3 is a section of a detail illustrating two positions which the nails assume in the act of securing the rubber heel on the shoe; Fig. 4 is another section of a detail illustrating a position which a nail 45 assumes when driven against a plate not constructed in accordance with my invention; Fig. 5 is a plan of a rubber heel containing a fastening plate of alternative construction, a portion of the heel being broken away and in section for the purpose of exposing a portion of the plate; Fig. 6 is a 50 section of a detail taken upon the line Y—Y, Fig. 5; Fig. 7 is a section of an alternative construction of rubber heel; Fig. 8 is an elevation of a portion of a shoe illustrating another alternative form of my invention, a portion of the heel being broken away and in section to expose a portion of the fastening plate; Fig. 9 is a plan of an alternative construction, part of the heel being broken away; Fig. 10 is a section on the line Z—Z of Fig. 9, and Fig. 11 is a section of a detail of a shoe and a detail of a heel of the construction shown in Figs. 9 and 10 shown nailed on the shoe.

55 Referring to the drawing, let A represent a rubber or other resilient heel and B a plate which is embedded in the heel, said plate being molded or vulcanized therein. One side of the plate facing the lower surface 60 of the heel is provided with a roughened surface C made by intersecting scratches or grooves 2, in which the points of the nails 3 which are used for attaching the heel to the shoe catch to prevent the points from 65 being deflected from their course when the nails are being driven through the rubber heel and into the shoe. The scratches or 70 grooves are close together and cover the entire surface of the plate or that zone or 75 zones through which it is intended to drive the nails. The scratches or grooves also 80 serve to weaken the plate, so that the nails will more readily perforate the plate when 85 driven through the rubber heel and into 90 the shoe. With this form of construction it is not necessary to have previously formed 95 holes in the rubber to register with holes in the plate, but the nail or nails may be driven in anywhere in the portion covered by the plate, and it will be sure of entering the plate without deflection or bending. When desired, the plate may be formed with 100 openings 4 of any suitable shape or location, through which the rubber constituting 105 the heel passes to more securely hold the plate embedded in the heel. A certain portion of the lower surface of the rubber heel indicated by 5 may be roughened or otherwise marked over the plate, so as to act as 110 a spotting means for positioning the nails to be driven through the plate and through the heel. In driving the nails through the plate, a bur 6 is formed, which acts as a reinforcement to assist in preventing the plate from buckling, and also to secure the nails, rubber heel and plate in place and together.

In Fig. 4, a plate 7 is illustrated having a smooth surface and a nail with its point deflected and bent when being driven through the heel. This objection is entirely overcome by my invention. The roughened and reinforcing surface of the plate may be formed by a mass of small indentations 8 as illustrated in Figs. 5 and 6 when desired, but it will be noted that these indentations or detents do not perforate the plate, but most effectively reinforce its surface against bending or buckling. The plate may be additionally reinforced by forming flanges 9 (see Fig. 7) around all of its edges. In Fig. 8 the plate B is shown applied to a full heel.

In the construction illustrated in Figs. 9 to 11 inclusive, the plate member is of a different design, illustrating one of many ways in which the invention can be modified. The inner surface 10 of the resilient body is concave and the outermost or lower surface 11 convex. When the heel is nailed onto the shoe, as illustrated in Fig. 11, the heel is drawn tightly against the lower flat surface of the heel portion by the plate and nails, the plate also being dished as shown to most effectively draw and hold the heel firmly against the flat lower surface of the shoe. A closer fitting joint is thus provided continuously around the edge of the heel and against the shoe, thus obviating the use of cement.

In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following claims.

Having described my invention, what I claim as new and desire to protect by Letters Patent is:—

1. A cushion heel provided with an easily penetrable substantially continuous plate embedded therein formed with detents in its lower surface for engaging and guiding points of nails driven through said heel and plate and into a shoe.

2. A cushion heel provided with an unbroken penetrable plate embedded therein formed with a rough surface facing the lower surface of the heel, for the purposes specified.

3. A cushion heel provided with a penetrable continuous plate embedded therein formed with a large number of nail point engaging detents.

4. A cushion heel provided with a penetrable continuous plate embedded therein formed with a rough surface weakened at a large number of points by a corresponding number of detents.

5. A cushion heel provided with a penetrable continuous surface detented to engage and prevent the points of nails deflecting or bending from their direct course through the heel and plate, said plate being reinforced to prevent buckling.

6. A cushion heel provided with a penetrable plate embedded therein and formed with a plurality of intersecting grooves on one of its faces for engaging and positively guiding the points of nails driven through said heel and plate and into the shoe.

7. As a new article of manufacture, a cushion heel provided with an imperforate metallic plate embedded therein, said plate being penetrable by the fastening means employed to unyieldingly secure the heel on a shoe.

In testimony whereof, I have signed my name to this specification.

FRANCIS A. NOLAN.
